PRESSER-FOOT FOR ZIGZAG-STITCHING ATTACHMENTS

John D. Karle, Roselle Park, N. J., assignor to
The Singer Manufacturing Company, Elizabeth, N. J., a corporation of New Jersey

Application October 25, 1932. Serial No. 639,391

6 Claims. (Cl. 112—235)

This invention relates to sewing machine presser-feet and more particularly to the type of presser-feet used with zigzag-stitching attachments.

5 In the drawings, Fig. 1 is a front elevation of a zigzag-stitching attachment with my improved presser-foot attached, showing the needle in its highest position and the position of the presser-foot and feed-dog at the completion of the right to left shifting movement.

10 Fig. 2 is an elevation similar to Figure 1 showing the position of the presser-foot and feed-dog after the left to right shifting movement has been partially executed.

15 Fig. 3 is a plan view of the presser-foot.

Fig. 4 is a front elevation of the presser-foot.

Fig. 5 is a side elevation and Fig. 6 is a disassembled perspective view of the presser-foot.

20 In the embodiment of this invention selected for illustration, 1 is the usual needle-bar bearing in which is journaled the usual reciprocating needle-bar 2. Secured to the needle-bar 2 by the usual set-screw 3 is a needle-clamp 4 having a laterally extending arm 5 to which is pivoted a 25 pawl 6 having a stop 7 and constantly urged in a counterclockwise direction by the coil-spring 8. Secured to the usual presser-bar (not shown) is a plate 9 having an upstanding inclined arm 10 and cross arm 11. Pivoted to the upstanding arm 10 at the pivot point 12 is a swinging frame 13 having a depending portion 14 and inwardly extending projections 15. Rotatably supported upon the upstanding arm 10 is a ratchet-wheel 16 rigidly connected with a cam-element 17 having 30 a plurality of circumferentially spaced projections 18. Slidably mounted upon the laterally extending arms 11 of the plate 9 is a slide-bar 19 having a depending portion 20 made integral therewith. The slide-bar 19 is provided with an 35 adjustable eccentric stop 21 and a knurled headed adjustable stop-screw 22. In the operation of the attachment, shortly after the needle 2' is out of the work the pawl 6 engages one of the teeth of the ratchet-wheel 16 and advances it one 40 step. This causes one of the circumferentially spaced projections 18 on the cam-element 17 to contact one of the inwardly extending projections 15 on the swinging frame 13, thereby causing the swinging frame 13 to vibrate. This vibratory motion is imparted to the slide-bar 19 by the 45 downwardly extending arm 14 of the swinging frame 13, thus causing the slide-bar 19 to vibrate laterally of the line of seam-formation.

The above described zigzag-stitching attachment 50 is substantially the same as that forming the

subject of my copending application Serial No. 578,262, filed Dec. 1, 1931, to which reference may be had for a more complete description.

The presser-foot, in its illustrated embodiment, comprises a shank 23 secured by the screw 60 24 to the depending portion 20 of the slide-bar 19. To the shank 23 is pivotally secured a sole-plate 25 by means of a pivot-pin 26 which is received by the outstanding lugs 27 on the shank 23. The sole-plate 25 is provided with a groove 65 28 which receives the pivot-pin 26 and is retained on the shank 23 by the retaining plate 29 having fingers 29' which extend over the pivot-pin 26, the retaining plate being fixed to the sole-plate by the screws 30. Through the above de- 70 scribed connection the sole-plate is free to tilt vertically relative to the shank. The sole-plate 25 is provided with a rectangular opening 31 at one side of the elongated needle aperture 32 in which is closely fitted a relatively thick rectangular shaped auxiliary presser-member 33 which extends below the work-engaging face of the sole-plate. Secured by the screw 34 to the upper face of the auxiliary presser-member 33 is a retaining plate 35 which extends over the sides 75 of the auxiliary presser-member and engages the upper face of the sole-plate. Secured to the sole-plate 25 by the screws 36 is a flat U-shaped spring 37 the free limbs 38 of which engage the upper face of the auxiliary presser-member and urge 80 it downwardly with respect to the sole-plate. 85

My improved presser-foot is designed for use for felling, and in Figures 1 and 2 I have shown a piece of material A folded upon itself as at b and with its edge a inturned making a fold c. 90 As will be observed in these figures the outer surface of the fold c contacts the edge 39 of the auxiliary presser-member 33, this edge 39 acting as a guide. It will also be observed that the serrated work-engaging faces of both the auxiliary presser-member and the sole-plate contact the material thereby firmly gripping it to facilitate the lateral shifting movement of the material by the zigzag attachment. It will be obvious from the foregoing description that the auxiliary presser-member acts as a guide for the material and, being yieldingly urged downward relative to the sole-plate, readily adjusts itself to materials of varying thickness. 95 100

It is apparent that the construction described is susceptible of variations, and, therefore, the privilege is reserved of resorting to all such legitimate changes therein as may be fairly embodied in the spirit and scope of the appended claims. 110

Having thus set forth the nature of the invention, what I claim herein is:—

1. A presser-foot for sewing machines comprising, a shank, a sole-plate having an elongated needle-aperture and pivoted thereto so as to tilt vertically, an auxiliary presser-member carried by said sole-plate and extending below the lower face thereof, said auxiliary presser-member having a smooth vertical edge which acts as a guide, and means for yieldingly urging said auxiliary presser-member downwardly relative to said sole-plate.

2. A presser-foot for sewing machines comprising, a shank, a sole-plate pivoted thereto so as to tilt vertically, an auxiliary presser-member extending through an aperture in said sole-plate, said auxiliary presser-member extending below the work-engaging face of said sole-plate and having a guiding edge, and means secured to said sole-plate for urging said auxiliary presser-member downwardly relative to said sole-plate.

3. A presser-foot for sewing machines comprising, a shank, a sole-plate provided with a needle-aperture and pivoted thereto so as to tilt vertically, and having a rectangular recess formed at one side of the needle-aperture, an auxiliary presser-member located in said opening and extending below the lower face of said sole-plate, and a U-shaped flat spring fixed to said sole-plate, the free limbs of which engage the upper

surface of the auxiliary presser-member and urge it downwardly with respect to said sole-plate.

4. In a sewing machine in combination, a member adapted to be jogged laterally of the line of seam formation, means under control of the needle-bar of the machine for jogging said member, a presser-foot attached to said member, and an auxiliary presser-member carried by said presser-foot, said auxiliary member extending below the work-engaging face of said presser-foot and having a substantially vertical edge which acts as a guide.

5. In combination with a zigzag-stitching attachment including a presser-foot having a shank and a sole-plate, an auxiliary presser-member carried by said sole-plate and extending below the work-engaging face thereof, said auxiliary presser-member having an edge forming a guide, and means for yieldingly urging said auxiliary presser-member downwardly.

6. A presser-foot for sewing machines comprising, a shank, a sole-plate having an elongated needle aperture carried thereby, an auxiliary presser-member carried by said sole-plate, said auxiliary presser-member having a vertical edge which extends below the lower face of the sole-plate and acts as a guide, and spring means for urging said auxiliary presser-member downwardly relative to said sole-plate.
